Primary Examiner — Michael A Pratt*(74) Attorney, Agent, or Firm* — Grace J. Fishel(57) **CLAIM**

The ornamental design for a trigger block, as shown.

DESCRIPTION

FIG. 1 is a front elevation of a trigger block showing my new design installed on the trigger guard of a firearm,

FIG. 2 is a first perspective view thereof in process of being installed on the trigger guard;

FIG. 3 is a second perspective view thereof in process of being removed from the trigger guard;

FIG. 4 is a top plan view thereof;

FIG. 5 is a left end view thereof;

FIG. 6 is a rear elevation thereof;

FIG. 7 is a right end view thereof;

FIG. 8 is a front elevation thereof;

FIG. 9 is a bottom plan view thereof; and,

FIG. 10 is an inside flattened view thereof.

The firearm shown in broken lines in FIGS. 1-3 and tabs shown in FIGS. 4-10 are not part of the design.
